UNITED STATES PATENT OFFICE.

THEODORE L. RICHMOND, OF BUFFALO, NEW YORK.

SUSPENSION-BEARING FOR PLATFORM-SCALES.

1,100,258.

Specification of Letters Patent. Patented June 16, 1912.

Application filed July 5, 1912. Serial No. 707,743.

To all whom it may concern:

Be it known that I, THEODORE L. RICHMOND, a citizen of the United States, residing at Buffalo, in the county of Erie and State of New York, have invented a new and useful Improvement in Suspension-Bearings for Platform-Scales, of which the following is a specification.

This invention relates more particularly to platform scales, such as wagon or railway scales, which are employed for weighing heavy objects. Scales of this kind have generally been so constructed that the parts of the platform knife-edge bearings were rigidly secured to the platform levers and the platform. Owing to the tendency of the platform to shift horizontally more or less when the load is moved onto and off of the same, causing the knife edges to grind against the bearings, it was found desirable in certain cases to suspend the platform from the knife edges in such a manner as to permit the same to swing to a certain extent without transmitting the motion of the platform to the platform levers and knife edges. This was accomplished by suspending the platform from the platform levers by two links depending from each knife edge bearing at opposite sides of the platform lever. This construction necessitated the use of a suitable equalizing device for distributing the pressure due to the load on the platform equally between the two links, and consequently causing an equal distribution of pressure on the platform knife edge.

The object of this invention is to produce a suspension bearing for platform scales in which only one link is employed which distributes the pressure evenly throughout the length of the knife edge, whereby the usual equalizing means can be dispensed with and the construction of scales of this kind accordingly simplified.

In the accompanying drawings: Figure 1 is a fragmentary transverse sectional elevation of a platform scale embodying the invention. Fig. 2 is a broken plan view of one of the platform levers and associated bearings. Fig. 3 is a transverse sectional elevation thereof on line 3—3, Fig. 2.

Like reference characters refer to like parts in the several figures.

The suspension bearings are illustrated in the drawings in connection with the usual system of platform supporting levers consisting of transverse levers fulcrumed ad-

jaacent to opposite sides of the platform and suitably connected to longitudinal levers which are fulcrumed adjacent to opposite ends of the platform and one of which is connected to the scale beam.

A represents two of the transverse platform levers, and a one of the longitudinal levers to which the transverse levers are connected by suitable knife edge pivots a'. Each of the platform levers has the usual fulcrum knife edge a² which bears on a suitable fixed stand a³ mounted on the foundation or abutments of the scale. All of these parts of the scale, except as hereinafter specified, may be of the usual or any suitable construction.

Each of the supporting beams or girders b of the scale platform rests on bifurcated supports or arches B, secured at their upper ends to the beam. Each of these arches straddles one of the platform levers A, the depending legs b' of the arch extending below the lower edge of the lever and being connected at their lower extremities by a pin or cross bar b² which rests in a loop or link C suspended from the platform lever A. The cross bar or pin b² is preferably removably secured in the arch B so as to facilitate the dismantling of the scale, and preferably has a groove b³ in which the loop or link rests.

In order to distribute the stresses of the platform load evenly over the platform bearing of the platform lever A by means of the single link C, the following construction is employed: The lever is provided with a vertical slot D through which the link C extends. The platform knife edge E is located at the upper edge of the lever and bridges the slot D, the slotted portion of the lever being preferably widened to strengthen the lever and afford an extended support for the knife edge. A bearing block F with a hardened bearing piece f bears on the knife edge E and the link C passes over and bears at its upper end on the bearing block, preferably in a groove f' therein. The lever is preferably provided at opposite sides with upwardly extending fingers or parts g which prevent the displacement of the bearing block F on the knife edge E. The link is adapted to swing on the bearing block F both lengthwise and crosswise relative to the lever A, so that in the use of the scale the platform is permitted a limited horizontal movement.

both longitudinally and transversely thereof without causing any grinding of the knife edge E on the bearing block F.

By means of the construction described it is made possible to employ only one link in the suspension bearing, and no equalizing means are necessary, since the load is centrally applied and evenly distributed throughout the platform knife edge, thereby simplifying the construction and reducing the cost of scales of this kind.

I claim as my invention:

1. In a platform scale, the combination of a platform lever having a vertical slot extending through the same, a platform knife edge resting on the upper face of the lever and bridging the slot, a bearing for said knife edge, a link extending through said slot and passing over and supported on said bearing, and means for supporting the platform from the lower part of said link.

2. In a platform scale, the combination of a platform lever having an enlarged portion and a vertical slot extending through said enlarged portion, a platform knife edge resting on the upper face of the enlarged portion of the lever and bridging said slot, a bearing for said knife edge, a link extending through said slot and passing over and supported on said bearing, and means for supporting the platform from the lower part of said link.

3. In a platform scale, the combination of a platform lever having a vertical slot extending through the same, the portions of said lever forming the side walls of the slot being of increased thickness at the upper face of the lever, a platform knife edge resting on the upper face of the lever and bridging the slot, a bearing for said knife edge, a link extending through said slot and passing over and supported on said bear-

ing, and means for supporting the platform from the lower part of said link.

4. In a platform scale, the combination of a platform lever having a vertical slot extending through the same, a platform knife edge resting on the upper face of the lever and bridging the slot, the side walls of said slot having integral portions which extend inwardly into said slot and outwardly beyond the outer edges of said side walls under said platform knife edge for supporting the same, a bearing for said knife edge, a link extending through said slot and passing over and supported on said bearing, and means for supporting the platform from the lower part of said link.

5. In a platform scale, the combination of a platform lever having a vertical hole extending through the same, a platform knife edge supported on the upper face of said lever adjacent to said hole and which is of greater length than the width of said hole, a bearing for said knife edge which bears substantially throughout the length of said knife edge, a link which is suspended from said bearing and which extends through said hole in the lever, a bifurcated support for the scale platform having downwardly extending legs and which straddles said platform lever, a pin connecting the lower extremities of said legs and resting on the lower end of said link, and means for preventing the pin from sliding relatively to said link.

Witness my hand, this 3rd day of July, 1912.

THEODORE L. RICHMOND.
